CLAIM

USPC D12/202, 204, 205, 206, 207, 208,
D12/209–213; D15/10, 33; D21/561,
D21/563

The ornamental design for a vehicle wheel, toy vehicle wheel, and/or replicas thereof as shown and described.

CPC B60B 1/00; B60B 1/08; B60B 1/10; B60B
1/12; B60B 3/02; B60B 3/04; B60B 3/06;
B60B 3/10; B60B 7/00; B60B 7/01;
B60B 7/02; B60B 7/04

DESCRIPTION

See application file for complete search history.

This application contains subject matter related to the following co-pending U.S. design patent application:
application Ser. No. 29/893,082, filed May 25, 2023 and
entitled "Vehicle Wheel, Toy Vehicle Wheel, and/or Replicas Thereof."

(56) **References Cited**

FIG. 1 is a perspective view of a vehicle wheel, toy vehicle wheel, and/or replicas thereof according to the design;
FIG. 2 is an additional perspective view thereof;
FIG. 3 is an additional perspective view thereof;
FIG. 4 is a front elevation view thereof; and,
FIG. 5 is a side elevation view thereof.
